ERNEST DAVIS, OF SYRACUSE, NEW YORK, ASSIGNOR TO THE PROSPERITY COMPANY, INC., OF SYRACUSE, NEW YORK, A CORPORATION OF NEW YORK

PRESSING MACHINE ELEMENT CONSTRUCTION FOR GARMENT AND LAUNDRY PRESSING MACHINES

Application filed December 28, 1928. Serial No. 329,038.

This invention relates to pressing elements for pressing machines and has for its object, a particularly simple and economical construction of a pressing element or head 5 formed for the most part of sheet metal.

The invention consists in the novel features and in the combinations and constructions hereinafter set forth and claimed.

In describing this invention, reference is had to the accompanying drawing in which like characters designate corresponding parts in all the views.

Figure 1 is a plan view of a press head embodying my invention.

Figures 2 and 3 are sectional views taken respectively, on lines 2—2, 3—3, Figure 1.

Figure 4 is a fragmentary side elevation of a pressing machine.

This pressing element or head for pressing machines comprises a press plate, a second plate overlying the press plate and formed of sheet metal and fixed to the press plate, a third plate overlying the second plate of sheet metal and having its margin secured 25 to the second plate and intermediate portions offset from the second plate and together therewith forming a chamber for a fluid medium. The press plate is spaced from the second plate to form a chamber for a heating 30 medium as steam, the press plate is also perforated, and a valve controlled conduit connecting the chamber and the space between the press plate and the second plate.

1 designates the press plate which is usually a casting of thick unflexible sheet steel, and 2 designates the second plate of sheet metal overlying the press plate 1 and spaced therefrom, the plate 2 being secured along its margins to the plate 1 and being spaced 40 at its margins from the plate 1 by spacing strips 3. The plate 1 is also formed with perforations 4 throughout its extent and these perforations communicate with the space between the plates 1, 2. This space is 45 usually filled with a heat distributing medium as metal wool 5.

A third plate 6 is secured at its margins to the plate 2 and has its intermediate portions offset to form a chamber for a heating 50 medium as steam. As illustrated, the plate

6 is formed with lengthwise corrugations which terminate short of the ends of the plate. Alternate corrugations rest upon and are secured to plate 2 as by welding. The intermediate corrugations provide passageways over the top of plate 2. It will be noted inasmuch as these corrugations terminate short of the ends of the plate 6 of which they are formed, the passageways formed by the intermediate corrugations 55 open into a chamber common to all the corrugations, thus providing for the circulation of the heating medium over a comparatively large portion of the surface of the plate 2. A suitable inlet 8 is provided at one end for steam and an outlet 9 at the other end. Usually, the corrugated plate 6 is overlaid with a sheet of heat insulating material 9^a and also by a sheet metal cover plate 10, the sheet of heat insulating material 9^a and the outer 60 sheet metal cover plate 10 are secured at their margins to the margin of the plate 6.

11 is a carrier by means of which the head is secured to a yoke lever 12 of a pressing machine. This carrier is connected to the press head 1 so that the strain or weight of the head is carried by the cast plate 1. The carrier 11 is connected to the press plate 1 by studs 13 slidable through the carrier 11 and extending through the plate 10, insulating sheet 9^a plates, 6 and 2 and threading into the press plate 1, these studs extending through the alternate corrugations of the plate 6 which are secured to the plate 2. Spacers or gaskets 14 are usually interposed 65 between the plates 1 and 2.

A conduit connects the steam chamber formed by the corrugated plate 6 and the space between the plates 1 and 2. This conduit comprises two sections 15 and 16 and a valve 17 connecting the sections. The section 15 opens into the chamber between one of the corrugations of the plate 6 and the plate 2; the section 16 extends through the space between two of the corrugations and 70 through the plate 2. The valve 17 is manually operated and extends through an opening 18 in the carrier 11.

In Figure 4, is shown one type of machine in which this pressing element is used, and 100

although the head above described is formed of sheet metal, either the head or the buck B or both may be formed of sheet metal. The buck B is stationary and suitably mounted on the frame F. The yoke lever 12 which carries the head is carried by the frame and actuated by any suitable mechanism carried by the frame.

The construction of the head is particularly economical and owing to the space between the plates 1 and 2, the steam that is to be projected through the perforations is maintained hot enough so that it will not condense while being distributed throughout the plate 1.

15 What I claim is:

1. In a garment or laundry pressing machine in combination a press plate; a second plate overlying the press plate and secured thereto; a third plate formed of sheet metal, 20 and formed so that its marginal edges and other portions of its area contact with said second plate, while other portions of the area of said third plate are spaced apart from the second plate to form a chamber for a fluid medium; means securing the third plate to the second plate; means for admitting fluid to the chamber; a carrier; and securing means operatively connected with the first plate and the carrier and extending through 25 the second and third plates.

2. In a garment or laundry pressing machine in combination a rigid pressing means having a pressing face formed on one side thereof; a sheet metal plate mounted on the other side thereof and formed so that its marginal edges and intermediate portions of its area contact with said rigid pressing means, while other portions of the area of said sheet metal plate are spaced apart from the rigid pressing means to form a chamber for a fluid medium; a carrier; and means connecting the carrier to the rigid pressing means.

3. In a garment or laundry pressing machine in combination a rigid pressing means having a pressing face formed on the lower side thereof; a sheet metal plate mounted on the upper side thereof and formed with corrugations so that its marginal edges and the 45 depressed parts of the corrugations contact with the upper side of said rigid pressing means, while the raised portions of the corrugations form chambers for a fluid medium; means securing the sheet metal plate to the rigid pressing means at their areas of contact; a carrier; and means securing the carrier to the rigid pressing means.

4. In a garment or laundry pressing machine in combination a rigid pressing means 50 having a pressing face formed on the lower side thereof; a sheet metal plate mounted on the upper side thereof with its marginal edges in contact with said lower side, and formed with parallel lengthwise corrugations and a transverse corrugation adjacent

one end thereof so that the depressed parts of the corrugations contact with the upper side of said rigid pressing means, while the raised portions of the corrugations form parallel chambers having a connecting chamber 70 at their ends; means securing the margins and depressed portions of the corrugations to the rigid pressing means; means for admitting fluid to the chambers; a carrier; and fastening means extending through the sheet metal plate to secure the rigid pressing means to the carrier.

5. In a garment or laundry pressing machine in combination a press plate; a second plate overlying the press plate and secured thereto; a third plate formed of sheet metal, 80 and formed so that its marginal edges and other portions of its area contact with said second plate, while other portions of the area of said third plate are spaced apart from the second plate to form a chamber for a fluid medium; means securing the third plate to the second plate; means for admitting fluid to the chamber; a carrier; and means extending through the second and third plates for securing the press plate to the carrier, said securing means being slidably mounted in the carrier, and springs between the carrier and the third plate.

6. In a garment or laundry pressing machine in combination a pressing element having a perforated press plate; a sheet metal plate overlying the press plate and having its marginal edges secured thereto; a corrugated plate of sheet metal overlying said sheet metal plate and having its marginal edges and the depressed portions of the corrugations secured to the sheet metal plate, said corrugations forming chambers over the sheet metal plate; means for admitting a heating medium into said chambers; a carrier for the pressing element; and means securing the pressing element to said carrier.

7. In a garment or laundry pressing machine in combination a pressing element including a perforated press plate; a sheet metal plate overlying the press plate and having its marginal edges secured thereto; a corrugated plate of sheet metal overlying said sheet metal plate and having its marginal edges secured thereto, the corrugations being parallel and terminating short of the end of the corrugated plate in a transverse corrugation; means securing the lowest part of each of the parallel corrugations to the sheet metal plate so that said corrugations form chambers which are connected at their ends by the chamber formed by the transverse corrugation; and means for admitting a heating medium into said chambers.

8. In a garment or laundry pressing machine in combination a pressing element including a perforated press plate; a sheet metal plate overlying the press plate and having its marginal edges secured thereto;

- a corrugated plate of sheet metal overlying said sheet metal plate and having its marginal edges secured thereto and an intermediate portion of its area spaced therefrom to form a chamber behind the perforations in the press plate; means for admitting a fluid into the chamber; a corrugated plate of sheet metal overlying said sheet metal plate and having its marginal edges and the depressed portions of the corrugations secured to said sheet metal plate, said corrugations forming chambers over the sheet metal plate; and means for admitting a heating medium into the chambers formed by the corrugated plate. 5
9. In a garment or laundry pressing machine in combination a pressing element including a perforated press plate; a sheet metal plate overlying the press plate and having its marginal edges secured thereto; a corrugated plate of sheet metal overlying said sheet metal plate and having its marginal edges secured thereto and an intermediate portion of its area spaced therefrom to form a chamber behind the perforations in the press plate; means for admitting a fluid into the chamber; a corrugated plate of sheet metal overlying said sheet metal plate and having its marginal edges secured thereto, the corrugations being parallel and terminating short of the end of the corrugated plate in a transverse corrugation; means securing the lowest part of each of the parallel corrugations to the sheet metal plate so that said corrugations form chambers which are connected at their ends by the chamber formed by the transverse corrugation; and means for admitting a heating medium into said chambers. 10
10. In a garment or laundry pressing machine in combination a pressing element including a rigid perforated pressing plate having a pressing face formed on one side thereof; a first sheet metal plate overlying the other side thereof and having its marginal edges secured thereto and an intermediate portion of its area spaced therefrom to form a chamber behind the perforations in the pressing plate; a second sheet metal plate overlying the first sheet metal plate and having its marginal edges secured thereto and an intermediate portion of its area spaced therefrom to form a heating chamber; means for admitting a heating medium to said chamber; and valve controlled means, between the chamber formed by the first sheet metal plate and the heating chamber, through which fluid may flow to the perforations in the pressing plate. 15
11. In a garment or laundry pressing machine in combination a rigid pressing means having a pressing face formed on one side thereof; a sheet metal plate mounted on the other side thereof and formed so that its marginal edges and intermediate portions of its area contact with said rigid pressing means, while other portions of the area of said third plate are spaced apart from the rigid pressing means to form a chamber for a heating medium; heat insulating material overlying the sheet metal plate; a cover plate over the heat insulating material; a carrier; and means connecting the carrier to the rigid pressing means. 20
12. In a garment or laundry pressing machine in combination a rigid pressing means having a pressing face formed on the lower side thereof; a sheet metal plate mounted on the upper side thereof with its marginal edges in contact with said lower side, and formed with parallel lengthwise corrugations and a transverse corrugation adjacent one end thereof so that the depressed parts of the corrugations contact with the upper side of said rigid pressing means while the raised portions of the corrugations form parallel chambers having a connecting chamber at their ends; means securing the margins and depressed portions of the corrugations to the rigid pressing means; means for admitting fluid to the chambers; a layer of heat insulating material overlying the sheet metal plate; a cover plate over the layer of heat insulating material; a carrier; and fastening means extending through the cover plate, heat insulating material, and sheet metal plate, to secure the rigid pressing means to the carrier. 25
13. In a garment or laundry pressing machine in combination a pressing element including a perforated press plate; a sheet metal plate overlying the press plate and having its marginal edges secured thereto; a corrugated plate of sheet metal overlying said sheet metal plate and having its marginal edges secured thereto and an intermediate portion of its area spaced therefrom to form a chamber behind the perforations in the press plate; means for admitting a fluid into the chamber; a corrugated plate of sheet metal overlying said sheet metal plate and having its marginal edges and the depressed portions of the corrugations secured to said sheet metal plate, said corrugations forming chambers over the sheet metal plate; means for admitting a heating medium into the chambers formed by the corrugated plate; a layer of heat insulating material overlying the corrugated plate; and a cover plate over the layer of heat insulating material. 30
- In testimony whereof, I have hereunto signed my name, at Syracuse, in the county of Onondaga and State of New York, this 21st day of December, 1928.
- ERNEST DAVIS. 125
